UNITED STATES PATENT OFFICE.

WALTER P. MURPHY, OF CHICAGO, ILLINOIS, ASSIGNOR TO P. H. MURPHY COMPANY,
OF PARNASSUS, PENNSYLVANIA, A CORPORATION OF PENNSYLVANIA.

CAR-ROOF.

1,250,206.

Specification of Letters Patent. Patented Dec. 18, 1917.

Application filed August 18, 1916. Serial No. 115,812.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

This invention relates to lining or insulation for freight cars, and particularly to car roofs of the type shown in my pending application, Ser. No. 59,938, filed November 6, 1915. The present application contains subject-matter divided out of said application Ser. No. 59,938.

15 The objects of the invention are to provide a smooth inside wall or ceiling for metal side walls or roofs, which is a non-conductor of heat and is damp-proof, and which will not sweat or collect moisture on the inside. Further objects of the invention relate to means for securing the lining in place in the car, and to the construction of the eaves portion of the roof and side walls.

20 The invention consists in arranging insulation inside of and adjacent to the metal side or roof plates, and in supporting the insulation by means riveted or otherwise secured to the points between the plates. The invention further consists in providing 25 a base plate for supporting and stiffening the roof along the eaves of the car, and for securing the roof to the car.

25 Further objects and details of the invention appear in connection with the following 35 description of the several embodiments of the invention illustrated in the accompanying drawings; and what the invention consists in is also stated in the appended claims.

30 In the drawings, wherein the same reference characters designate the same parts in the several views,

Figure 1 is a plan view of a portion of the end of a car embodying one form of the invention;

45 Fig. 2 is an end elevation of the same; Figs. 3 and 4 are longitudinal cross-sections of the same on the lines 3-3 and 4-4, respectively, in Fig. 1, looking in the direction of the arrows;

50 Fig. 5 is a detail perspective view of the end of a lining support;

Fig. 6 is a transvers cross-section of the roof shown in Figs. 1 to 4, inclusive, on the line 6-6 in Fig. 1, looking in the direction 55 of the arrows;

Fig. 7 is a cross-section of a riveted seam, showing a modified form of roof sheet joint and insulation support;

Fig. 8 is a transverse cross-section of the roof at the eaves of another modification of the invention, showing a bulb shaped seam cover and a wooden lining under the roof sheets;

Fig. 9 is a longitudinal section on the line 9-9 in Fig. 8, further illustrating the modification shown in Fig. 8; and

Figs. 10 and 11 are views similar to Figs. 8 and 9, respectively, of another form of supporting and attaching means for the sides and ends of the roof.

In Figs. 1 to 6 of the drawings, a roof embodying the invention is shown applied to a box car having wood side plates 11, but it may be applied to other forms of car body. The end plate 12 likewise is made of wood, 75 and has a top board 13 bolted to its outer face for supporting the roof at the ends of the car. The siding boards 14 are secured to the outer face of the side plate, and their upper ends are covered by wood fascia 80 boards 15.

The roof is made of heavy metal roof sheets 16 which are arranged crosswise of the car, spanning its width from eaves to eaves, and supported at their eaves ends on angle iron eaves strips 17. The side margins of the roof sheets are bent up, forming straight flanges 18 along both sides of each sheet. The flanges 18 of adjacent roof sheets are arranged in juxtaposition with a lining support 19 between them and are covered by inverted U-shaped seam covers 20, which are riveted along their lower edges to the flanges of the roof sheets, thus constituting the load carrying members of the roof. The lower 95 edges of the lining supports project below the roof sheets and have oppositely disposed flanges 21 for supporting the roof lining. The seam covers extend from eaves to eaves, and their ends are bent down over the ends 100 of the joints between the roof sheets. The seam covers are of varying height, being highest at the middle of the car and decreasing in height toward the eaves. I am aware of a structure in which the load supporting 105 members have flanges supporting a lining and also have roof flanges secured thereto, but such a construction requires heavy supporting members and does not answer the purposes of this invention.

Below the roof sheets, wood lining boards 22 are arranged lengthwise of the car. The ends of the lining boards rest on the horizontally disposed flanges 21. These flanges 5 are bent from the lower edge of the supporting strips 19 in alternation upon opposite sides, forming a series of short flanges as shown in Fig. 5. At the ends of the car, the lining boards rest on the top edges of 10 the end plates and butt against the top boards 13. Beading strips 24 are nailed to the side plates and end plates in the angle under the lining boards.

At the ends of the car the roof sheets are 15 spaced above and project over the tops of the end plates, and are riveted to angle iron end strips 25 which extend across the end of the car outside of the top boards 13 on the end plates. The vertical legs of the end 20 strips 25 extend down alongside of the top boards and are secured thereto.

The running boards 26 are arranged lengthwise of the car at the ridge, above the tops of the seam covers 20, and are securely 25 bolted to metal running board saddles 27. The running board saddles are angle shaped, and are mounted one on each side of a seam cover at the ridge. Their downwardly projecting flanges are riveted to opposite sides 30 of the seam cover on each side of the ridge line. The ends of the running boards project over the ends of the car and are bolted to plates 28, which are supported from the end plates 12 by means of brackets 29 which 35 are bolted to the running boards and plates 28.

In the modification of the invention shown in Fig. 7, the lining boards 30 are spaced below the roof sheets, and are supported on 40 the lower flanges of inverted T-shape lining supports 31. The vertical flange of the lining support is riveted between the adjacent flanges 18 of the roof sheets.

In the modification shown in Figs. 8 and 9, the seam cover 32 has a bulb shaped top edge 33, and lateral flanges 34 along the lower edges of its side walls. Two narrow strips of sheet metal 35 are arranged vertically side by side and riveted between the flanges 18 of 50 each roof sheet joint; the lower edges of these strips 35 projecting below the under surface of the roof. Thin wooden boards 36 are arranged beneath each roof sheet, extending lengthwise of the car between the 55 joints, and the lower edges of the metal strips 35 are bent apart, forming lateral flanges 37 upon which the ends of the boards 36 rest. This lining of boards may be applied after the roof is in place on the car, 60 the flanges 37 being bent under the ends of the boards after they are fitted in place. The eaves strips 38 and end strips are supported clear of the side plates 39 and end plates by means of angle brackets 40 having 65 their horizontal legs bolted on top of the

side and end plates with their vertical legs hanging over the outer edges thereof. The vertical legs of the angle brackets 40 are arranged flatwise against the inner sides of the vertical flanges of the angle shape eaves and end strips, and are riveted thereto. This construction permits of the roof sheets, seam covers, angle strips and brackets, being assembled off of the car and riveted up, and lifted on to the car as a whole. The variations in the length and width of the roofs, and of the cars over the side plates, can be accommodated to each other by suitably disposing the holes in the horizontal legs of the brackets 40 to take the bolts 41 which 80 secure them to the side and end plates.

In the modification shown in Figs. 10 and 11, the eaves strips 42, and the end strips likewise, are pressed or rolled metal members, with their outer edges flanged down to 85 make drip edges 43. They are arranged with their inner edges projecting over the top flanges of the side and end plates and riveted or bolted thereto. The inner edges of the strips 42 may be formed with downwardly offset portions 44 for supporting them above the top flanges of the side and end plates. The seam cover 45 illustrated in Figs. 10 and 11 has a flattened bulb shape top to 90 strengthen it both vertically and laterally.

Other modifications of the form and arrangement of the parts may be made in view of the foregoing description of the invention; and the invention is not restricted to the forms and arrangements shown in the 100 drawings.

I claim the following as my invention:

1. A metal roof comprising metal plates having flanges along their meeting edges constituting load carrying members, in combination with an insulating lining comprising panels arranged next to said plates on their inner sides, and lining supporting members arranged between said panels inside of said plates and each having an outwardly projecting portion riveted between said plate flanges, said lining supporting members having oppositely disposed portions inside of said panels for securing the latter in place.

2. A metal roof comprising metal plates having flanges along their meeting edges constituting load carrying members, in combination with an insulating lining comprising panels arranged next to said plates on their inner sides, and lining supporting members arranged between said panels inside of said plates and each having an outwardly projecting portion riveted between said plate flanges, said lining supporting members having oppositely disposed tongues along their inner edges inside of said panels for securing the latter in place.

3. A metal roof comprising metal plates having flanges along their meeting edges

- constituting load carrying members, in combination with an insulating lining comprising panels arranged next to said plates on their inner sides, and lining supporting members arranged between said panels inside of said plates and each having an outwardly projecting portion riveted between said plate flanges, said lining supporting members having oppositely disposed shelves 10 arranged in alternation on opposite sides and extending inside of said panels for securing the latter in place.
4. In combination, in a plate metal roof construction having standing seams constituting load carrying members, a combined seam stiffener and lining support consisting of web members riveted into the standing seams of said plates to cause them to work together throughout their length to support 20 said roof, said web members having laterally projecting flanges spaced inside of said plates, and lining strips arranged between said flanges and said plates.
5. A stiffened transverse seam construction for insulated, metal roofs comprising roof plates having stiffening flanges along their side edges extending from eaves to eaves, sheet metal stiffeners of inverted T shape having their webs vertically disposed 30 between the flanges of adjacent plates and their horizontal flanges spaced below said plates for supporting insulation, flanged seam caps over said plate flanges and vertically disposed webs, and rivets securing said 35 plate flanges, stiffeners and caps rigidly together throughout their length whereby they constitute a unitary transverse support for the roof.
6. A self-supporting car roof comprising 40 metal roof sheets arranged crosswise of the car and having their ends spaced above and projecting over the top edges of the car sides, longitudinal stiffening members arranged along the eaves and having portions 45 spaced from the side of the car and secured to the eaves ends of said roof sheets, said roof stiffening members having portions projecting inward over the car sides and supported thereon, whereby said members accommodate crosswise misalignment between 50 the eaves of the roof and the sides of the car are secured thereto to brace the car and hold the roof in place.
7. A self-supporting car roof comprising 55 metal roof sheets arranged crosswise of the car and having their ends spaced above and projecting over the tops of the side walls of the car, longitudinal stiffening members arranged along the eaves and depending below 60 the roof sheets, said stiffening members being secured to the eaves ends of said roof sheets outside of the side walls of the car, and roof supporting members secured to said eaves stiffening members below the roof 65 sheets and having horizontal portions ex- tending inwardly from the eaves over the tops of the side walls of the car and secured thereto, said supporting members extending inwardly to accommodate crosswise misalignment between the eaves stiffeners and the sides of the car and secured thereto to brace the car and hold the roof in place.
8. A car roof comprising metal roof sheets arranged crosswise of the car and overhanging along the eaves, said roof sheets having 70 their side margins securely joined together, transverse stiffening members extending from eaves to eaves and rigidly secured to said roof sheets throughout their length, longitudinal stiffening members arranged 75 along the eaves beneath the ends of the roof sheets and secured thereto, said eaves stiffening members being spaced outside of the top edges of the side walls of the car and comprising roof supporting members projecting from their inner sides and extending inwardly and resting upon the top edges of the car sides, said supporting members being secured to the car sides to hold them 80 from bowing.
9. A car roof comprising roof sheets having upturned side flanges, said roof sheets being arranged side by side with their flanges extending crosswise of the car, seam covers having tops and side walls arranged 85 over said pairs of adjacent flanges with their side walls riveted to said flanges to constitute external carlines, strips of sheet metal arranged in pairs between the flanges of adjacent sheets and riveted thereto to form 90 co-operating portions of said carlines, the lower edges of said strips projecting below said sheets and being spread apart to form lateral flanges, and roof lining arranged in sections beneath the roof sheets between 95 said strips and supported thereby, said roof lining supporting said roof sheets between the carlines.
10. A self-supporting car roof comprising roof sheets having upturned side flanges, 100 said roof sheets being arranged parallel to each other with their flanges extending crosswise of the car, seam covers having tops and side walls arranged over said pairs of adjacent flanges with their side walls riveted 105 to said flanges from end to end, said seam covers being deeper at the ridge than at the eaves and made of heavier metal than said roof sheets, stiffening webs arranged between the flanges of adjacent sheets and secured thereto like said seam covers, the lower edges of said stiffening webs projecting below said sheets, and roof lining arranged in sections beneath the roof sheets between 110 said stiffening webs and supported thereby, 115 whereby said seam covers, stiffening webs, and roof sheet flanges stiffen said roof at the seams and support said lining and roof sheets.
11. A self-supporting car roof comprising 120

- 4.
11. Roof sheets having upturned side flanges, said roof sheets being arranged parallel to each other with their flanges extending crosswise of the car, seam covers having tops and side walls arranged over said pairs of adjacent flanges with their side walls riveted to said flanges, said seam covers having sufficient vertical dimension that they and the sheets together constitute a self-supporting roof structure, lining supports which are continuous from eaves to eaves arranged between the flanges of adjacent sheets and riveted thereto from end to end, the lower edges of said lining supports projecting below said sheets, whereby said seam covers, lining supports and roof sheet flanges constitute transverse ribs which stiffen said roof, and roof lining arranged beneath the roof sheets between said lining supports and supported therefrom, said roof lining supporting said roof sheets between said ribs.
12. A car roof comprising metal roof sheets extending from eaves to eaves and having upstanding flanges along their side margins, and cover strips arranged over said flanges and riveted thereto through
13. A self-supporting car roof comprising roof sheets arched upwardly between their ends and having upturned side flanges, said roof sheets being arranged parallel to each other with their flanges extending cross-wise of the car and rigidly secured at their ends above the side plates, lining supports which are continuous from eaves to eaves arranged between the flanges of adjacent sheets and riveted thereto from end to end, and roof lining arranged below the roof sheets and lining supports and supported therefrom, said roof lining supporting said roof sheets between their edges, whereby said lining supports and roof sheet flanges constitute transverse arched ribs which stiffen said roof and support said lining and roof sheets.

Signed at St. Louis, Missouri, this 12th day of August, 1916.

WALTER P. MURPHY.
